SHEET METAL CONTAINER

Filed May 27, 1929

INVENTOR
Victor Odquist
BY John Q. Carpenter
ATTORNEY

UNITED STATES PATENT OFFICE

VICTOR ODQUIST, OF YONKERS, NEW YORK, ASSIGNOR TO AMERICAN CAN COMPANY, OF NEW YORK, N. Y., A CORPORATION OF NEW JERSEY

SHEET METAL CONTAINER

Application filed May 27, 1929. Serial No. 366,442.

The present invention relates to a new and useful improvement in sheet metal containers and more particularly to a container having a bail or handle pivotally connected therewith.

The principal object of the present invention is the provision of a metallic container having a bail formed of a flat strip of sheet material so shaped as to provide pivotal connection with the container by having its edges turned over to enclose a channel in which there are positioned extended and headed rivets secured to the container body.

A further important object of the present invention is the provision of a container bail formed from a flat strip of sheet material and having pivotal and sliding connection with rivets projecting from opposite points in the wall of the container whereby the bail may be used as a handle, or may be moved into horizontal position and slid into close position adjacent the container wall.

A further object of the invention is the provision of a container bail formed from a single strip of sheet material without slots or perforations and being reinforced by a curling of all of its edges, thereby effecting a reinforced pivotal and sliding connection with the container body and presenting a smooth bail with an unbroken external surface.

Numerous other objects and advantages of the invention will be apparent as it is better understood from the following description, which, taken in connection with the accompanying drawings, discloses a preferred embodiment thereof.

Referring to the drawings:—

Figure 1 is a front elevation, partly in section and partly broken away, of a container and its bail made according to the present invention, the bail being shown in container carrying position.

Fig. 2 is a side elevation of the container and bail with the bail shown in non-carrying position, parts being broken away.

Fig. 3 is an enlarged fragmentary sectional view taken substantially along line 3—3 in Fig. 2 illustrating a portion of the

container in elevation and a portion of the bail in container carrying position.

Fig. 4 is a transverse sectional view of the bail taken substantially along line 4—4 in Fig. 1.

The improved container of the present invention comprises a container body 11 which may be closed with a top 12 double seamed or otherwise secured thereto.

Container body 11 is preferably provided with an extending horizontal bead 13 spaced a slight distance from and beneath the container top 12. A bail or handle 14 is provided for carrying the container and comprises a flat semi-circular body portion 15 having its side edges curled inwardly and bent back or hemmed at 16 (Fig. 4) the bail beyond body portion 15 having its side edges curled inward by and spaced from the wall of the bail as at 17. These curled edges, in turn, extend into semi-circular end edges curled inwardly at 18 to provide a channel 19 at each end of the bail.

A pair of sheet metal clips 21 are secured by rivets 22 or in other suitable manner to opposite positions on the upper end of the container body 11. A pivotal member 23 is projected outwardly from each metal clip 21 and is upset or expanded to provide an enlarged head 24. Each head 24 rests within one of the channels 19 and the two pivot members form a sliding and pivotal connection between the container body and the bail. Each of the curled end edges 18 confining each channel 19 closely fits the enlarged head 24 of each pivot member 23 when the bail 14 is in vertical or container carrying position and these edges form a support for the container. The bail 14 is greatly reinforced by the curled edges 16, 17 and 18 and a strong pivotal connection is thus produced between container and bail.

While a one piece pivotal member 23 is disclosed in the drawings as a preferred construction, other pivot members having enlarged heads may be used with satisfactory results. For example, pivot member 23 may comprise a separate rivet having an enlarged head and secured either to a clip 21 or directly to the container body wall.

Bail 14 has free pivotal action on the pivots 23, the terminal walls of the channel 19 at such time moving freely over the pivot heads 24. When bail 14 is moved to horizontal or 5 non-carrying position (Fig. 2) it can be pushed toward the center of the container body 11, the terminals thereof sliding freely over the pivot heads and the latter sliding within the channel 19. In the final inward 10 position bail 14 lies closely against the outer wall of the container 11 (Fig. 2), the bail being wholly confined within the space between the bead 13 and the container top 12. In this condition the container may be rolled 15 through a standard form of labeling machine and a label applied thereto without any interference of the bail 14.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A sheet metal container including a container body, a pair of flat headed pivot members secured to the body near its top and positioned at diametrically opposite points, and a sheet metal bail having its edges turned over to form longitudinal channels, the heads 30 of said pivot members being positioned within the longitudinal channels to form pivotal engagement between said container body and said bail and the turned-over parts of said edges extending into the path of said heads 35 to arrest the same.

2. A sheet metal container including a cylindrical container body, a pair of flat headed pivot members secured to the body near its top and positioned at diametrically opposite 45 points, a semi-circular sheet metal bail conforming in curvature to the wall of the cylindrical body and having its side and end edges turned over to enclose longitudinal channels, the heads of said pivot members being positioned within the longitudinal channels of 50 the bail and having sliding and rotary movement therein, whereby said bail may be moved into carrying or non-carrying position and the turned-over parts of said edges 55 extending into the path of said heads to arrest the same.

3. A sheet metal container including a cylindrical container body, a pair of flat headed pivot members secured to the body near its 60 top and positioned at diametrically opposite points, a semi-circular sheet metal bail conforming in curvature to the wall of the cylindrical body and having its side and end edges turned over to enclose longitudinal channels, 65 the heads of said pivot members being positioned

within the longitudinal channels of the bail and having sliding movement therein whereby said bail is positioned in close proximity to the container wall and having rotary movement therein whereby said bail 70 is moved into container carrying position and the turned-over parts of said edges extending into the path of said heads to arrest the same.
